UNITED STATES PATENT OFFICE.

EDWARD M. BROOKS, OF FORT WAYNE, INDIANA, ASSIGNOR OF ONE-HALF TO SAMUEL H. BRADSHAW, OF FORT WAYNE, INDIANA.

WINDOW-FASTENER.

1,401,941.

Specification of Letters Patent. Patented Dec. 27, 1921.

Application filed February 4, 1921. Serial No. 442,346.

To all whom it may concern:

Be it known that I, EDWARD M. BROOKS, a subject of the King of Great Britain, and resident of Fort Wayne in the county of 5 Allen and State of Indiana, have invented certain new and useful Improvements in Window-Fasteners, of which the following is a specification.

This invention relates to improvements 10 in window fasteners and the object thereof is to provide a device of its class adapted to secure windows in a manner to prevent opening movement thereof being applied from the exterior, and which will be effective at all positions of the window.

The object of the invention is accomplished by the construction illustrated in the accompanying drawings in which:

Figure 1 is a perspective view showing the 20 invention applied to a pair of window sashes of the usual type;

Fig. 2 is a detail perspective view of one of the ratchet members;

Fig. 3 is a perspective view of the supporting bracket for the ratchet member;

Fig. 4 is an end view of the ratchet member mounted in connection with its supporting bracket, there being parts broken away and in section;

Fig. 5 is an elevation showing portions of 30 a pair of window sashes with the invention applied thereto; and

Fig. 6 is another view of the ratchet member showing a cross section through its 35 hub and the rod upon which it is mounted.

Similar numerals of reference indicate corresponding parts throughout the several views and referring now to the same:

1 and 2 are upper and lower sashes of a 40 window of usual construction adapted to be raised and lowered. 3 are notched bars that are fitted into the inner faces of the upper sash 1 respectively at the sides thereof. Upon the top of the sash 2, at each side 45 thereof is mounted a bracket 4, and in each bracket is mounted a ratchet member 5 having a hub 6 that extends through an opening 7 in the bracket. A slot 8 is made in the hub of the ratchet member and a screw 9 in 50 the bracket extends into the slot 8 in the hub of the bracket so that the ratchet is

loosely secured. A rod 10 is connected at its respective ends in the hubs 6 of the corresponding brackets, there being a pin 11 extending through each hub and engaging the 55 rod so that as one ratchet member is turned upon its axis, the other ratchet member will likewise be turned. The pin 11 extends loosely through an opening 10' in the rod 10 so as to admit of slight play between the 60 rod and ratchet, the purpose being to permit the ratchet sufficient freedom as to independently engage the notches of the corresponding bars.

The bracket 4 has a projection 12 at its 65 outer end having a pair of cavities 13 made in the upper face thereof, and the ratchet member 5 has a pocket 14 which contains a spring 15 and ball 16. The spring acts against the ball tending to press it against 70 the projection 12, so that as the ratchet is turned upon its hub the ball will become pressed into one or the other of the cavities 13 and tend to hold the ratchet in position 75 accordingly. Thus, when the ratchets are 80 moved into engagement with the notched bars 3 the ratchets tend to remain engaged therewith, because of the tendency of the spring pressed balls to remain engaged in the cavities. Likewise when the ratchets 85 are moved out of engagement with the notched bars and the balls become shifted so as to engage the opposite cavities and the ratchets are thereby held from engaging the 90 notched bars.

In using the invention the window sashes are secured by manipulating one or the other of the ratchets so as to engage its notched bar which has the effect, because of the connection of the rod 10, of likewise 95 moving the other ratchet into engagement with its corresponding notched bar. When the ratchets are thus positioned, the upper sash may be moved upwardly or the lower sash may be moved downwardly until the 95 window is completely closed. But, because of the engagement of the ratchets which are mounted on the lower sash with the notched bars which are mounted upon the upper sash, the opening movement of either sash relative to the other is prevented. By manipulating 100 either one or the other of the ratchets

both may be disengaged from the notched bars and thus permit free movements of the sashes.

What I claim is:

- 5 In a securing device for a pair of window sashes, a pair of ratchet members secured to one sash, one at each side thereof; a rod connecting the ratchet members; means in connection with the other sash adapted to
- 10 be engaged by the ratchets and prevent

opening movement of one sash relative to the other; and means in connection with each ratchet to hold the same in engaging and disengaging positions.

In testimony whereof I affix my signature 15 in presence of two witnesses.

EDWARD M. BROOKS.
